LOCK

Arthur J. Doyle, Cleveland, Ohio, assignor to The Youngstown Steel Door Company, Cleveland, Ohio, a corporation of Ohio

Application February 2, 1943, Serial No. 474,430

7 Claims. (Cl. 292—283)

This invention relates to locks and particularly to locks for sliding car doors.

It is an object of this invention to provide locks for sliding doors capable of absorbing slack created by the movement of the doors in closing direction.

A further object is to provide locks for sliding doors embodying a hasp and a pin and capable of absorbing slack created by the movement of the doors in closing direction and constructed to prevent undesirable upward movement of the pin.

Other objects of the invention will become clear as the description thereof proceeds.

In the drawing forming part of this specification:

Fig. 1 is a fragmentary elevation showing a lock embodying the invention applied to a double door construction for railway house cars.

Fig. 2 is a horizontal section taken on line 2—2 of Fig. 1.

Fig. 3 is a vertical section taken on line 3—3 of Fig. 1.

The instant invention is illustrated in a lock adapted for application to the double doors of a railway house car with which it has its greatest utility. It is to be understood, however, that the lock may also be utilized in conjunction with single doors of railway cars.

In the double door application illustrated the lock embodies a hasp fastener 10 riveted upon one of the horizontal corrugations 11 of the metallic panel 12 of the main door 13 of the double door construction. The free end of the neck 14 of the hasp fastener extends through a vertical corrugation 15 formed in the panel 12 adjacent to the forward edge thereof and with which the horizontal corrugations 11 merge. The hasp fastener 10 is reinforced by means of a member 16 disposed upon the inside of the horizontal corrugation upon which the hasp fastener is mounted. The hasp fastener reinforcement is secured to the horizontal corrugation by the rivets which secure the hasp fastener to the corrugation, and extends into the vertical corrugation 15. The free end of the neck of the hasp fastener projects through an opening in the hasp fastener reinforcement and is preferably welded to the reinforcement, as more clearly illustrated in Fig. 2 of the drawings.

The hasp fastener swingably supports a hasp 17 by extending through an eye 18 formed in the hasp. The hasp 17 embodies a straight outer wall 19 and laterally spaced inner wall 20 which is inclined horizontally relative to the main door 13 and also inclined vertically relative to the main

door. The front and rear walls 19 and 20 of the hasp are connected by the longitudinally spaced side walls 21 and 22 so as to form an aperture for the reception of a locking pin, as hereinafter explained. The rear wall 20 of the hasp is provided with reinforcing ribs 23 and 24 which in the operative position of the lock are adapted to bear against a lock bracket 25 secured to the auxiliary door 26 of the double door construction.

10 The auxiliary door 26 comprises a metallic panel 27 whose construction is substantially similar to that of the metallic panel 12 of the main door 13 with the exception that certain of the horizontal corrugations 28 of the metallic panel 27 terminate a greater distance inwardly from the forward edge of the auxiliary door panel than the horizontal corrugations 11 formed in the metallic panel 12 of the main door. This construction provides a flat portion 29 in the auxiliary door panel 27 upon which the lock bracket 25 is secured so that the projection of the lock bracket outwardly from the auxiliary door is reduced. It will be understood that the horizontal corrugations 28 and the front marginal construction of 15 the auxiliary door may be the same as that of the main door and that the lock bracket 25 will be correspondingly modified so as to fit upon the corrugations where the projection of the lock bracket is not limited.

30 The lock bracket 25, which is preferably in the form of a casting, is provided with vertically spaced housing members 30 and 31 between which the hasp 17 is received when the lock is in its operative position so that the aperture formed by the walls 19—22, inclusive, of the hasp is aligned with the openings provided by the housings 30 and 31. In the operative position of the hasp the rear wall 20 and the reinforcing ribs 23 35 and 24 are adapted to bear against the lock bracket 25 which is reinforced by means of an angle 32 disposed upon the inner face of the metallic panel 27 and secured thereto and to the lock bracket as by means of rivets 33. The height 40 of the reinforcing angle member 32 is preferably the same as that of the lock bracket. The reinforcing angle member 32 is also secured as by means of rivets 34 to a metallic post 35 rigidly secured to and carried by the auxiliary door, as 45 more clearly appears from Fig. 2 of the drawings.

50 The lock bracket 25 is formed with a rib 36 which carries a projection, preferably in the form of a rivet 37, for a reason which will hereinafter appear. At its lower portion the lock bracket is

formed with a rib 38 provided with a seal slot 39.

The lock bracket is adapted to carry a locking pin 40 which is slidably received within the housing members 30 and 31. In the embodiment of the invention illustrated the locking pin 40 is formed with a straight front face 41 and a rear face 42 which is inclined similar to the wall 20 of hasp 17, as is clearly shown in Figs. 2 and 3 of the drawings. The inclination of the rear face of the pin is similar to that of the rear wall 20 of the hasp 17 with which wall the pin cooperates, as hereinafter explained. The side faces 43 and 44 of the pin 40 are vertical. The side face 43 of the pin is formed with a shoulder 45 adapted to engage the projection 37 so as to prevent loss of the pin. The pin 40 is also formed with an ear 46 having a seal slot 47 which is adapted to be aligned with the seal slot 39 so as to receive a ribbon seal.

The lock is shown in its operative position with the main and auxiliary doors fully closed in Fig. 1 of the drawing. In this position, as well as in all operative positions of the lock, the pin extends through the housings 30 and 31 and through the aperture formed in the hasp 17. By reason of the instant invention the main and auxiliary doors of the double door construction may be secured together by the lock even prior to the time when the main and auxiliary doors are fully closed. The relationship between the locking pin, the hasp and the lock bracket when the lock is in its operative position is more clearly shown in Figs. 2 and 3 of the drawing from which it will be observed that the inclined portions of the pin and the wall 20 of the hasp are in engagement and the front face of the pin and the housing members 30 and 31 are in engagement. In the event that the doors are not fully closed, it will be apparent that the relationship between the inclined portions of the pin and the rear wall 20 of the hasp will prevent a movement of the main door in opening direction away from the auxiliary door but that movement of the main door toward the auxiliary door may occur. Upon such occurrence the hasp which is carried by the main door will move in the same direction as the main door so that it will be released from engagement with the inclined portion of the pin. When this release occurs the pin will drop by the action of gravity until the space created by such movement is filled by a wider portion of the pin. The relationship between the pin, the hasp and the lock bracket, illustrated in Fig. 3 of the drawing, is thereby again restored. Movement of the main door in opening direction is thus prohibited and this action of the lock will continue until the main and auxiliary doors are fully closed. Lashing of the main door and consequent wear upon the door and the lock parts are avoided.

By virtue of the instant invention the side edges of the pin are straight and take-up of any clearance created by any movement of the main door in closing direction is obtained by means of the inclination of the rear face of the pin. This construction eliminates the possibility of upward jumping of the pin when the car is subjected to impact since the stresses imposed upon the inclined face of the pin tending to prevent jumping of the pin are in excess of those stresses tending to cause jumping of the pin. Danger of shearing of the sealing ribbons is thereby avoided.

It will be apparent that numerous changes and modifications in the details of the invention will be clear to those skilled in the art. It is in-

tended, therefore, that all such modifications and changes be comprehended within this invention, which is to be limited only by the scope of the claims appended hereto.

5 I claim:

1. A lock for a sliding door comprising a bracket adapted to be secured to a relatively stationary member associated with said door, said bracket having vertically spaced housing members, a hasp 10 adapted to be swingably secured to said door, and a pin slidably in said housing members, said hasp having a longitudinally extending wall adapted to lie between said housing members and bear against said bracket, the front face of said wall being inclined both horizontally and vertically relative to said door, the rear face of said pin being similarly inclined and adapted to engage the front face of said wall, the front face of said pin being adapted to bear against the housing members of said bracket.

2. A lock for a sliding door comprising a bracket adapted to be secured to a relatively stationary member associated with said door, said bracket having vertically spaced housing members, a hasp adapted to be swingably secured to said door, and a pin having downwardly converging front and rear faces slidable in said housing members, said hasp having a longitudinally extending wall adapted to lie between said housing members and bear against said bracket, the front face of said wall being inclined both horizontally and vertically relative to said door, the rear face of said pin being similarly inclined and adapted to engage the front face of said wall, the front face of said pin being adapted to bear against the housing members of said bracket.

3. A lock for a sliding door comprising a bracket adapted to be secured to a relatively stationary member associated with said door, said bracket having vertically spaced housing members, a hasp adapted to be swingably secured to said door, and a pin slidably in said housing members, said hasp having laterally spaced longitudinally extending walls and connecting side walls defining an aperture adapted to receive said pin, a face of one of said longitudinally extending walls being inclined both horizontally and vertically relative to said door, a face of said pin being similarly inclined and adapted to engage said face of said one hasp wall, the opposite face of said pin being adapted to bear against the housing members of said bracket.

4. A lock for a sliding door member having a relatively stationary member adjacent thereto comprising a bracket adapted to be fastened to one of said members, a pin slidably supported by said bracket, means adapted to be secured to the other of said members, said means embodying a longitudinally extending wall, the front face of said wall being inclined both horizontally and vertically relative to said door, the rear face of said pin being similarly inclined and adapted to engage said front face of said wall, the front face of said pin being adapted to bear against said bracket.

5. A lock for a sliding door member having a relatively stationary member adjacent thereto comprising a bracket adapted to be fastened to one of said members, a pin having downwardly converging front and rear faces slidably supported by said bracket, means adapted to be secured to the other of said members, said means embodying a longitudinally extending wall, the front face of said wall being inclined both horizontally and vertically relative to said door, the front face of said pin being adapted to bear against the housing members of said bracket.

rear face of said pin being similarly inclined and adapted to engage said front face of said wall, the front face of said pin being adapted to bear against said bracket.

6. A lock for a sliding door member having a relatively stationary member adjacent thereto comprising a bracket adapted to be fastened to one of said members, a pin slidably supported by said bracket, means adapted to be secured to the other of said members, said means embodying a longitudinally extending wall, a face of said wall being inclined both horizontally and vertically relative to said door, a face of said pin being similarly inclined and adapted to engage said face of said wall, said pin being adapted to bear against said bracket. 15

7. A lock for a sliding door member having a relatively stationary member adjacent thereto comprising a bracket adapted to be fastened to one of said members, a pin having downwardly converging front and rear faces slidably supported by said brackets, means adapted to be secured to the other of said members, said means embodying a longitudinally extending wall, a face of said wall being inclined both horizontally and vertically relative to said door, a face of said pin being similarly inclined and adapted to engage said face of said wall, said pin being adapted to bear against said bracket.

ARTHUR J. DOYLE.
